United States Patent Office

Des. 233,827
Patented Dec. 3, 1974

233,827

BOTTLE

Misdrahi Henry, 71 Blvd. Brune,
Paris, France 75014

Filed May 21, 1973, Ser. No. 361,867

Term of patent 14 years

Int. Cl. D9—01

U.S. CL. D9—71

FIG. 1 is an elevational view of a bottle showing my new design;

FIG. 2 is an elevational view showing the side opposite that seen in FIG. 1;

FIG. 3 is a top plan view;

FIG. 4 is a bottom plan view;

FIG. 5 is an elevational view looking from the left of FIG. 1; and

FIG. 6 is an elevational view looking from the right of FIG. 1.

I claim:

The ornamental design for a bottle, substantially as shown.
